COMBINATION CONTAINER AND STRAW

Mary Tate and William W. Ower, Englewood, N. J.

Application August 24, 1932, Serial No. 630,323

5 Claims. (Cl. 215—11)

The invention is a container having a straw provided therein in which the straw is made of a cellulose or translucent material and the container is provided with a cover having an opening with a removable closure therefor.

One object of the invention is to provide a container similar to a soft drink bottle having a straw provided therein and in which it is not necessary to remove the bottle closure in order 10 to drink the contents thereof thru the straw.

Another object of the invention is to provide a straw or container of a cellulose or translucent material.

Another object of the invention is to provide a straw for a container in which the material used 15 is impervious to water or the like.

Another object of the invention is to provide a straw or the like in which the necessity of coating the straw with paraffin or the like is eliminated.

20 A further object of the invention is to provide a closure for a container having a removable flap covering an opening in the closure so that the opening may be opened without removing the cap.

25 And a still further object of the invention is to provide a container, straw or the like which is of a simple and economical construction.

With these ends in view the invention embodies 30 a bottle having a cap with an opening therein and a removable flap forming a closure for said opening, and in combination therewith a straw or a container made of a cellulose or translucent material.

Other features and advantages of the invention 35 will appear from the following description taken in connection with the drawing, wherein:

Figure 1 is a view showing a bottle having a straw contained therein.

Figure 2 is a view showing a side elevation of a 40 bottle cap with part broken away showing an opening in which a straw may be provided.

Figure 3 is a plan view of the bottle cap.

Figure 4 is a view showing a straw.

Figure 5 is a view showing a cup that may be 45 made of a cellulose or translucent material.

In the drawing the device is shown as it would be made wherein numeral 1 indicates a straw, numeral 2 a bottle, and numeral 3 a cap forming a closure for said bottle.

50 The straw 1 may be made of any material and of any design or description. It is preferred to make the straw of a colored cellophane which is substantially transparent so that when incorporated in the bottle, as shown in Figure 1, it will 55 show thru the bottle and anyone can readily

observe the interior of the straw and therefore determine whether or not it is clean and unobstructed. It will be noted that straws are normally made of a fibrous material and then coated with paraffin or the like which forms a waterproof covering whereas by making the straws of cellophane or other cellulose materials it will not be necessary to coat them with paraffin and they will be impervious to water or moisture at all times. The coating operation is, therefore, 60 eliminated as well as the paraffin taste when using the straw. It will be noted that the cellophane or the like may be provided in plain or variegated colors and the colors may be associated with various products if desired. It will also be 65 noted that drinking cups 4, as shown in Figure 5, or other similar products may be made of the same material which would be impervious to water and which will also eliminate the step required to coat these devices with paraffin. 70 These products may also be made of any color or design.

In Figure 1 the straw is shown in combination with a bottle of the soft drink type and the bottle is closed with a cap 3 that is crimped over 80 the upper edge thereof and the cap is provided with an opening 5 in which the material from the head of the cap from which the opening is formed is bent inward forming prongs 6 which 85 form guides for the upper end of the straw. It will be noted that the cap is placed upon the bottle and then the straw placed thru the opening with the upper end of the straw extending upward to the upper surface of the cap or to the point 6 and a flap 7 is placed on the cap with 90 soft solder or the like, with the solder extending from the point 8 to the point 9 and the opposite end 10 of the flap free. This will form a complete seal for the bottle and when in place the straw 1 will be sealed therein. The end 10 of the 95 flap is free so that when it is desired to open the bottle the free end 10 may be bent upward from the point 8, as indicated by the dotted lines 11, and this will give sufficient purchase so that the remainder of the flap may readily be pulled 100 from the cap. When the flap is removed the buoyancy of the fluid in the bottle will raise the straw 1 to the position indicated by the dotted lines 12 shown in Figure 1 and the straw may then be gripped by hand or held between the lips 105 to draw the contents out of the bottle. It will be noted that when used for pop or the like straws of different colors may be used to indicate different products and labels on the bottles may be dispensed with so that bottles may be readily 110

kept in ice water or the like without danger of losing the labels. It will also be understood that the straws will add an attractive feature to the bottles and will therefore have a considerable advantage as an advertising novelty.

It will be understood that straws or containers of cellophane, cellulose products or translucent material may be made of any other shape or description and used for any other purpose.

- 10 It will be understood that changes may be made in the construction without departing from the spirit of the invention. One of which changes may be in the use of a straw in a bottle of any other type or having a closure of any other design, another may be in the use of other means for holding the straw in the bottle and still another may be in the use of other means of removing the straw from the bottle.

The construction will be readily understood 20 from the foregoing description. In use the straw or container may be provided as shown and described and when filling the bottles the caps with the openings therein may be placed upon the bottles in the usual manner, the straws may 25 then be placed therein thru the openings and the flaps may then be installed upon the caps. The bottles may then be supplied or used in the usual manner.

Having thus fully described the invention what 30 we claim as new and desire to secure by Letters Patent, is:

1. A bottle, a cap having an opening therein forming a closure for said bottle, a straw in said bottle with the upper end held in said opening, and a flap soft soldered on said cap over said opening and forming a closure therefor.
2. A bottle, a cap with an opening therein forming a closure for said bottle, downwardly extending projections around said opening, a straw in said bottle with the upper end held be-

tween said projections, and a flap cemented to the cap forming a closure for sealing said opening.

3. In combination, a bottle, a cap secured to said bottle, an opening thru said cap, a cover plate soft soldered to said cap and sealing said opening, a straw in said bottle with the upper end corresponding with said opening, and means holding the upper end of said straw directly below said opening.

4. In combination, a bottle, a closure for said bottle, said closure having an opening therethru, readily removable means sealing said opening, a straw in said bottle positioned with the upper end directly below said opening, and means holding the upper end of said straw, said straw adapted to move upward thru the opening by the buoyancy of a fluid in the bottle when the means for sealing the opening is removed.

5. The combination with a bottle of the type having a ridge at the open end thereof adapted 95 to receive and hold a closure; of a closure of the stamped metal type adapted to be crimped over the ridge of said bottle and in which the closure is provided with an opening with prongs formed of the metal stamped from the opening extending downward into the bottle, said closure having a secondary closure covering and sealing said opening and adapted to be readily removed with the closure in place, and also of a straw positioned in said bottle and with the upper end held between 100 the downwardly projecting prongs from the opening of the closure, said straw adapted to be raised by the buoyancy of a fluid in the bottle so that the upper end thereof will pass upward thru the opening as the secondary closure is removed 110 thereby making it possible to use the straw without removing the bottle closure.
